CLAIM

The ornamental design for a ceiling fan motor housing, as shown and described.

DESCRIPTION

FIG. 1 is a top perspective view of a ceiling fan motor housing showing my new design, shown in the environment of a ceiling fan;

FIG. 2 is a bottom perspective view of the ceiling fan motor housing of FIG. 1, but shown without the ceiling fan environment;

FIG. 3 is a top view thereof;

FIG. 4 is a bottom view thereof;

FIG. 5 is a front side view thereof, with the rear side view being a mirror image thereof; and,

FIG. 6 is a right side view thereof, with the left side view being a mirror image thereof.

The broken lines shown in FIG. 1 illustrate environmental structure, and the broken lines in the remaining views illustrate portions of the ceiling fan motor housing. None of the broken lines form part of the claimed design.
